CLAIM

The ornamental design of an element of a shoe upper, as shown and described.

DESCRIPTION

FIG. 1 is a right side elevational view of an element of a shoe upper showing my new design. The broken line showing a shoe outline is for illustrative purposes only and forms no part of the claimed invention.

FIG. 2 is a top plan view thereof;

FIG. 3 is a right side elevational view thereof;

FIG. 4 is a front elevational view thereof; and

FIG. 5 is a rear elevational view thereof.

Fig. 1.

Fig. 2.

Fig. 3.

Fig. 4.

Fig. 5.
